UNITED STATES PATENT OFFICE.

WILLIAM WOLFE, OF ST. LOUIS, MISSOURI.

COMBINED LIFT-CUTTING, ASSEMBLING, AND HEEL-BUILDING MACHINE.

1,163,300.

Specification of Letters Patent.

Patented Dec. 7, 1915.

Application filed August 17, 1912. Serial No. 715,536.

To all whom it may concern:

Be it known that I, WILLIAM WOLFE, a citizen of the United States, residing in the city of St. Louis and State of Missouri, have 5 invented new and useful Improvements in Combined Lift-Cutting, Assembling, and Heel-Building Machines, of which the following is a specification.

This invention relates to the art of heel 10 building, and has for its object to provide a novel combined lift cutting, assembling, and heel building machine.

Heretofore, so far as I am aware the cutting of the lifts, either whole or pieced, has 15 been in practice conducted as a distinct operation, the cut lifts being supplied to an operator in certain sizes and thicknesses, according to the character of heel he may be instructed to build, a large number of each size 20 of lift entering into the construction of the heel being placed in separate compartments within his reach. These lifts are selected one at a time by the operator and piled one upon the other, after having paste applied 25 thereto, the lifts being compiled on a machine which subsequently is actuated to shape, compress, and nail them together. This practice, which, so far as I am aware, 30 is universal in the shoe industry, necessarily requires the manufacturer to carry an enormous number of lifts in stock, so that, according to the character of heel to be built, 35 the required number of lifts of the requisite size and thickness may be supplied to the operators.

It is the object of my invention to perform all of the operations entering into the building of a heel with the use of a single machine, which is practically automatic in operation. That is to say, I aim 40 to provide a machine which will enable a single operator to cut the various sizes and thicknesses of lifts entering into the heel he is required to make, apply paste to the lifts, assemble them in a mold, compress them, and finally nail them together. By 45 this invention the cutting of the lifts by operators other than those building the heel is rendered unnecessary, and hence the whole lift cutting department, as a separate 50 institution of a factory, may be abolished, and likewise the necessity for the storage of a large quantity of prepared lifts be obviated.

55 My invention comprises, in a general way, a rotatable head having a series of cutting

dies slidably mounted therein, with means for depressing said dies at stated intervals, and means for causing the head to be automatically rotated at will for a given distance; an automatic paste-applying device; a rotatable mold-carrying table in which the cut and pasted lifts are deposited from the dies; and a nailing device carried by one of said dies with means for driving a nail 60 therefrom through the lifts in the mold. The number of dies mounted in the rotatable head may be sufficient in number and vary in size so as to include all sizes of lifts which will ordinarily be made for given 65 classes of shoes. In addition, the dies are made removable so that other sizes or shapes of dies may be inserted in the head, the openings for the dies being large enough to receive a series of the largest size dies 70 that will ever be used, so that, if desired, the larger dies can be removed and smaller dies inserted by using appropriate bushings, as will be well understood by those skilled in 75 the art. By this means a single machine 80 may be made adaptable for use with all sizes and shapes of heels. In like manner the molds for receiving the cut lifts will be sufficiently large to receive the highest and the largest heel, and their interior dimensions 85 will be decreased by an insertion of suitable blanks, according to the shape and size of the heel being formed. These matters are all within the range of mechanical skill, and need not be described more fully. 90

In the accompanying drawings—Figure 1 is a view in side elevation of my improved machine; Fig. 2 is a plan view thereof; Fig. 3 is a section of the upper part of the machine on the line 3—3 of Fig. 2; Fig. 4 is a horizontal sectional view taken on the line 4—4 of Fig. 1; Fig. 5 is a broken plan view, partly in section, showing one of the dies and part of the mechanism for rotating the head carrying the dies; Fig. 6 is a section on the line 6—6 of Fig. 5; Fig. 7 is a broken plan view of a portion of the mold-carrying table, and of the heel-receiving table, illustrating the mechanism for discharging the heels from the former on to the latter; Fig. 8 is a section on the line 8—8 of Fig. 7; Fig. 9 is a broken plan view, partly in section, showing the cutting block and the mechanism for rotating the same; Fig. 10 is a view in side elevation of the same parts; Fig. 11 is a perspective view of one of the cutting dies; Fig. 12 is a broken view in side

elevation showing the paste-applying device; Fig. 13 is a view in front elevation of the same parts; Fig. 14 is a sectional view, partly broken away, taken on the line 14—14 of Fig. 1, showing the ratchet mechanism for operating the heel-receiving table and a part of the mechanism for pushing the heels on to said table; Fig. 15 illustrates a modification in the means for discharging the heel-blank from the heel mold; Fig. 16 is a sectional view on the line 16—16 of Fig. 15; Fig. 17 is a broken section on an enlarged scale, taken on the line 17—17 of Fig. 4, illustrating a part of the driving mechanism; Fig. 18 is a broken plan view on the same scale and showing the same parts illustrated in Fig. 17; and Fig. 19 is a view in rear elevation on the same scale and showing the same parts illustrated in Figs. 17 and 18.

Referring now to the drawings, 1 indicates the base of the machine on which is mounted a circular standard 2 having rotatably mounted thereon, near the upper end thereof, a circular head 3. The column 2 has an integral portion 4, projecting beyond the head 3, this upwardly extending portion being bifurcated to provide a bearing space for a lever-arm 5, which is pivoted therein by means of a bolt 6 passing through apertures in the bifurcated portion. The bolt 6 is extended a considerable distance to one side of the part 4, as indicated at 7, and near its outer end is provided with an aperture in which works a plunger 8, operated in a manner hereinafter described. The head 3 is provided around its circumference, and at points removed from its periphery, with equi-distant, vertically-disposed recesses 9, in which are removably seated a series of cutting dies 10, one of which is shown in detail in Fig. 11. These cutting dies, with the exception of the last one of a series, to be later described, are all of the same construction, varying only in size, and are of the shape of a lift to be cut, being provided at their lower end with a beveled cutting edge 12. The dies are made hollow and within each of the dies is mounted a plunger 13, which is provided on one face with a pointer 14 working through an opening 15 in the corresponding face of the die, and moving over a graduated scale 16 on such face of the die, adjacent to the side of the opening, so that as the lifts are cut the plunger 13 will be raised thereby and the pointer indicate on the scale 16 the thickness of the lift. For convenience I provide a second opening 17 on one or both sides of the die, and the part of the plunger operating in front of this opening is provided with a scale 18 so that the operator, by looking at this part of the die, can ascertain the thickness of the lift cut by comparing the scale with the upper edge of the opening 17. For a similar purpose a scale may be applied on

the flat face of the plunger 13 corresponding to that part appearing through the opening 15, but at the top of the plunger, as indicated at 20, so that the distance the respective marks of the scale will appear above the upper edge of the die will indicate the thickness of the lift. Either one or all of the scales described may be employed.

As stated, all of the dies, except the last one of a series, have the construction shown in Fig. 11. When the last lift is cut, pasted and applied, however, it is necessary to nail the compiled lifts together, and with this object in view the last die of a series, is provided with a nailing device, this construction being shown in Fig. 3, and on an enlarged scale in Fig. 6. In this construction the die 10 is provided with a plunger formed in two parts 21, 22, the upper part 21 being formed with a recess 23, in which is housed a coil spring 24, the two parts of the plunger being secured after the insertion of the spring by one or more screws 25. An aperture 26 extends vertically and centrally through the plunger as a whole, and in this aperture is mounted a nail driver 27, which is normally held in an upward position by the spring 24 bearing against a collar 28 secured on the nail driver. Adjacent to the aperture 26 there is provided a second aperture 29 extending from the top of the plunger to near the lower end thereof, where it communicates with the aperture 26, the opening in the wall of the plunger between the apertures 26 and 29 being large enough to permit a nail 30 inserted in the aperture 29 to fall into the aperture 26 below the lower end of the nail driver 27. At the lower end of the aperture 29 a leaf-spring 31 is secured, the free end of which extends across the aperture 26 to thereby prevent the nail 30 from falling out of such aperture, but yielding to permit the discharge of the nail on the descent of the nail driver 27. Each die 10 is provided at its lower end with a slot 32, in which works the end of a pin 33 secured in the lower end of the plunger 22, which thereby prevents the plunger from falling out of the die, and allows limited upper movement thereof. On opposite sides of each recess 9 in the head 3 two smaller recesses are provided, in each of which is housed a coil spring 34 which bears against a lug 35 secured on the die 10 near the top thereof. Screws 36 mounted in the top of the head 3 have eccentric heads adapted to be turned over the lugs 35 to limit the upward movement of the die.

The dies and the nail driver operate as follows: Mounted in the outer free end of the lever-arm 5 is a screw bolt 37 having a hand wheel 38 and a lock nut 39 to enable the bolt to be adjusted in the proper position in the lever-arm and locked in such position. On the lower end of this screw bolt is mount-

ed a hollow hammer 40 which is adapted to engage the top of each die and press the same downward as the outer end of the lever-arm 5 is depressed. The hammer is made hollow to permit the rise of the plunger in the die. This movement of the lever-arm is effected through the medium of a rod 41 pivotally secured to the opposite end of the lever-arm to that carrying the hammer, the lower end of said rod being provided with a ring 42 in which works an eccentric 43, these parts being shown in dotted lines in Fig. 17. The eccentric 43 is fixedly secured on a cross shaft 44 on which is mounted a loose pulley 45 and a fast pulley 46. A belt-shifter 47, slidably mounted on a short bearing rod 48, embraces the driving belt 49, and by manipulating this belt-shifter through the medium of a lever 50, bell-crank lever 50^a and link 50^b, the belt is shifted from the loose to the fast pulley in the usual manner, to operate the machine. The lever 50 is controlled by a spring 51, and the operator presses said lever to transfer the belt to the fast pulley to enable the machine to make one cycle of movement, and on releasing the lever the spring presses it upward, thereby automatically transferring the belt to the loose pulley to permit movement of the machine to cease. The friction between the movable parts of the machine is such as to cause it to stop after the driving power has been removed, the operator soon learning how long to keep the driving belt on the fast pulley. This form of drive control is preferred by many manufacturers for their machines, but I wish it to be understood that I do not limit my invention to the particular form of driving mechanism shown, as obviously a well known clutch drive could be employed, with means for positively stopping the machine after one cycle of movement, such device being well known in the art and needing no illustration. When the eccentric 43 is actuated the rod 41 will be alternately raised and lowered, the upward movement of the rod causing the free end of the lever-arm 5 to descend and depress the die 10 which may be under the hammer 40. The lever-arm 5, near its point of pivotal connection with the rod 41, is provided with an outwardly-extending arm 52, on the outer end of which is pivotally mounted the upper end of a link 53. The lower end of the link 53 is pivotally secured to a throw-lever 54 which is pivotally mounted at 55 in the end of a bracket 56 secured by bolts 57 to the upper part 4 of the column 2. The inner end of the throw lever 54 is bifurcated, and embraces a bearing block 58 provided on the plunger 8 (see Fig. 3) to which it is pivotally mounted by means of a pivot pin 59.

From the above construction it will be seen that as the inner end of the lever-arm 5 is thrown upward by the rod 41 the outer

end of the throw-lever 54 will be depressed thereby moving the plunger 8 downward into the aperture 26 where it engages the top of the nail-driver 27 and depresses it to drive the nail, which had previously been dropped into the aperture 24, into the compiled lifts. Extending outward from one side of the column 2 is a bracket 60 having at its outer end a vertical extension forming a standard 61. Rotatably mounted on the top of the standard 61 is a circular mold-carrying table 62 having a series of recesses formed in its upper surface for the reception of molds 63. Four of such recesses and molds are shown in the drawing (see Fig. 82), such molds being arranged directly opposite each other, or at equal distances apart, so that when one mold is under the nail driving die (Fig. 3) the next mold will lie adjacent to the heel-blank receiving board, 85 presently described, and this position of the respective molds occurs in each quarter revolution of the mold-carrying table 62. Depending from the bottom of the table 62 under each of the recesses containing a mold is a bracket 64 (Figs. 3 and 8), in which is mounted a plunger 65 which is normally pressed upward by a coil spring 66 located between the bottom of the bracket 64 and a collar 67 secured on the plunger. This 95 spring tends normally to press the plunger 65 upward, but such action is restrained by a shouldered pawl 68, yielding downwardly only, and controlled by a spring 69, the said pawl being mounted on a depending portion 100 of the head opposite the bracket 64, as shown more clearly in Fig. 3. Removably mounted on the top of the plunger 65 is a plunger-head 70, which, in its depressed position, shown in Fig. 8, forms the bottom of the mold 63. Initially said plunger-head 70 occupies a position at the top of the mold, as shown at the left of Fig. 3, and also in Fig. 15. It is made removable, so that a larger or smaller plunger-head may be substituted, according to the size of mold being used. The plunger 65 is provided on one side with a series of ratchet teeth 71, which are engaged by the pawl 68 so that the plunger can descend against the resistance of the spring 66 as the lifts are pressed into the mold 63, the pawl, as stated, preventing the plunger from moving upward during the operation of filling the mold. The pawl 68 is mounted on a plate 72 which is pivotally mounted by means of a bolt 73 on the under side of the table 62. At certain intervals, as later referred to, the plate 72 will be turned on its pivot 73 to release the pawl from engagement with the teeth 71 and allow the plunger 65 to rise. A set screw 74, having a friction disk 75 on its ends, is turned to cause the friction disk to engage the plunger 65 more or less firmly so that the plunger 65 will be caused to rise gradually. It 135

is stopped, with its upper side flush with the surface of the mold-carrying table, by means of a lug 75^a on the bracket 64 engaging the collar 67.

5 In order to rotate the head 3 I provide the following mechanism: Extending upward through the column 2, and rotatably mounted therein, is a rod 76 having secured thereon near its upper end an arm 77 (Fig. 6) 10 extending through and working in an elongated aperture 78, and having pivotally mounted on its outer end a shouldered ratchet 79 yielding in one direction only under the influence of a weight 80. On the under side of the head 3 there is provided a circular series of ratchet teeth 81 with which the pawl 79 engages. The rod 76, at its lower end (see Fig. 4) is provided with a crank-arm 82, which latter is provided at 15 its outer end with a slot 83 in which engages a pin 84 passing vertically through a lever 85. Extending outward from the column 2 is a bifurcated bracket 86 (see Figs. 1 and 4) which provides a recess for supporting 20 the lever 85. At its inner end the lever 85 has pivotally mounted thereon at 87 an end-piece 88 provided at its end with a hook 89, the pivotal connection 87 being a shouldered one so that the end-piece cannot descend below the horizontal, but is free to move upwardly. It is held normally in the horizontal position by means of a spring 90, (indicated by dotted lines) secured at one end to the end-piece, and at its other to the base 1. 25 The parts just described are shown only in plan in Fig. 4, but the arrangement will be made clear by an inspection of the bottom of Fig. 1, where identically the same construction of lever is mounted on the opposite side 30 of the base. This lever is indicated by 91, and is pivotally connected at 92 to an arm 93 secured on a rod 94 rotatably mounted at its lower end in a bearing 95 on the base, and at its upper end extending through the standard 61 of the mold-carrying table and being journaled in the top thereof, as shown in Fig. 3. Pivotally connected to the outer end 35 of the lever 91, as indicated at 96, is an end-piece 97 having a hook 98, the said end-piece 97 having a shouldered connection at 96 so that it may not descend below the horizontal but be free to move upwardly. It is normally held to the horizontal by means of a spring 99 secured at one end to the end-piece 50 and at its other to the base.

The numeral 100 indicates a throw-lever which is pivotally mounted by a slotted connection at its lower end on the base, as indicated at 101, and at its upper end is provided with a knee-piece 102 which has a tongue 103 slidably mounted in a groove provided in an arm 104 extending at right angles to a bracket 105 mounted on the frame of the machine. The inner end of 55 the lever 91 is provided with a slot 106 in

which works a pin 107 mounted on the throw-lever 100. The hook 98 on the end-piece 97 is adapted to be engaged by a pin 108 secured near the periphery of a disk 109 mounted on the cross shaft 44. This engagement is effected by the operator pressing the knee-piece 102 outward, whereby the engagement of the throw-lever 100 with the lever 91 at 107 will cause the outer end of the lever 91 to be thrown inward on the pin 75 92 as a pivot, so that as the disk 109 turns it will engage the hook 98 and draw the lever 91 inward, this operation continuing until the hook 98 has been carried to the opposite side of the disk, when the pin 108 80 will move out of engagement with the hook. The lever 91 is then automatically retracted to the position shown in Fig. 1 by means of a spring 110 secured at one end to the lever and at the other to the pin 107, or to some 85 other part of the throw-lever 100. After the throw-lever 100 is released it is automatically turned to normal position by means of a spring 111 secured at one end to the lever 91, and at its other to a post 112 90 projecting upwardly from the base 1. The inward movement of the lever 91, as above described, will cause a partial rotation of the shaft 94 through the action of the arm 93. Mounted on the shaft 94 near the upper 95 end thereof is a collar 113 from which projects an arm through an opening 114 in the side of the standard 61, said arm having mounted on its outer end a ratchet similar to the ratchet 79 above described, said ratchet 100 engaging a circular series of teeth 116 provided on the under side of the mold-carrying table 62. As the shaft 94 is rotated the pawl 115 engages with a tooth 116 and causes a quarter rotation of the mold-carrying table 62. 105

The lever 85 corresponds to and operates in the same manner as the lever 91, its throw-lever, however, being shown only in section in Fig. 4 and being indicated by the numeral 117, the numeral 118 indicating the pin connecting it with the lever 85. This lever is operated by a pin 119 secured near the periphery of a disk 120, which, in turn, is secured on the shaft 44. A portion of the knee-piece of the throw-lever 117 is shown in Fig. 2, and is indicated by the numeral 121. By moving this outward in the same manner as described with reference to the lever 100, the end-piece 88 will be thrown inward so that the pin 119 can engage with the hook 89 and draw said lever 85 inward. In this operation the rod 76 will be given a quarter revolution through the medium of the arm 82, thereby, through the arm 77 secured on the rod 76, causing the ratchet 79 to engage one of the circular series of teeth 81 and rotate the head 3 a given distance. The lever 85 is returned to normal position by a spring 122 in the same manner as the 120 125 126 127 128 129

lever 91, and as these levers are so drawn backward their respective shafts 76 and 94 will be turned in the reverse direction to that previously described, and the ratchets 5 79 and 115 will ride over the teeth on the under side of the head and mold-carrying table, respectively. After the throw-lever 117 has been pressed outward it is drawn backward to normal position, when released, 10 by means of a spring 123, secured at one end to a post 124 and at its other end to the lever 85. The numeral 125 indicates the cutting block which supports the leather while the lift is being cut by a die 10. This block is 15 supported on a bracket arm 126 projecting outward from the column 2, and is rotatably mounted thereon. Near its base the cutting block is surrounded by a series of ratchet teeth 127 with which engages a gravity pawl 128 mounted on the end of a rod 129. The other end of this rod is pivotally connected to a bell-crank lever 130 which is, in turn, pivotally mounted on a bracket 131 secured on a frame member 132. The other arm of 20 the bell-crank lever is pivotally connected at 133 to the rod 41 so that as the said rod is alternately raised and lowered the pawl 128 will ride over, or engage, the teeth of the ratchet 127, as the case may be, and cause 25 the cutting block to be turned, the purpose of this being to present a different surface beneath the dies, so as to increase the life of the cutting block by preventing the same part of the surface thereof being always 30 under the cutting dies. After the heel lifts have been assembled in the mold 63 and nailed together the next step is to cause the heel blank to be discharged from the mold. 35 This is accomplished by providing a lug 134 on the frame member 132, before referred to, in the path of the arm 72 carrying the pawl 68, so that as said table is rotated the projecting end of the arm 72 will strike the lug 134, thereby throwing the pawl 68 out 40 of engagement with the ratchet teeth 71. When this occurs the spring 66 will cause the plunger 65 to rise, the friction screw 74 insuring that this rise shall be gradual, this movement continuing until the plunger-head 70 on which the heel blank rests reaches a position flush with the surface of 45 the mold-carrying table, as shown at the left of Fig. 3. The next step is to discharge the heel blank on to the heel-receiving board 50 135. This board is removably supported on a table 136, which is slidably mounted on ways 137 provided on the upper side of an auxiliary frame 138, shown more clearly in Fig. 1.

55 The automatic discharge of the heel-blanks on to the board 135 is effected by the following mechanism: Slidably mounted in bearings in the lower part of the frame 138 is a bar 139 (see Figs. 1, 2, 8 and 14) which 60 is normally pressed outward or toward the

board 135 by means of a spring 140. Secured to the bar 139, near the outer end thereof, is an inwardly curved arm 141 having a transverse groove 142 provided in its upper surface near its point of connection 70 with the bar 139. Depending from the under side of the mold-carrying table are four striker arms 143 arranged at equal distances apart, which, as the mold-carrying table revolves, are adapted to successively engage 75 the curved arm 141 and thereby force the bar 139 inward against the resistance of the spring 140. This continues until the particular striker arm engaging the curved arm 141 reaches the groove 142, when the engagement 80 of these two parts is released and the spring 140 throws the bar 139 outward. Secured on the bar 139 is a vertically-disposed rod 144 which extends to a point slightly above the upper surface of the mold-carrying table 85 62 where it is bent at right angles to itself to extend over said table parallel with the surface thereof, as indicated at 145, and is provided at its outer end with a push plate 146. The push plate 146 is located, when 90 the spring 140 is in its retracted position, directly behind the mold lying in front of the board 135, and the location of the lug 134 is such that the heel blank, indicated by the numeral 147, will be discharged from 95 the mold as the latter reaches the position referred to, such position of the parts being shown in Fig. 7. As the arm 141 is released in the manner above described, the push plate 146 carried by the rod 145 will be 100 thrown outward, thereby discharging the heel on to the board 135. This operation is repeated in each cycle of movement of the machine. The board 135, as shown more clearly in Fig. 2, is divided into compartments 105 by means of vertical parallel partitions 148, and each compartment is designed to receive a certain number of heels. As one compartment is filled the board is moved to bring the adjacent compartment opposite 110 the mold, and this movement is effected as follows: Pivoted in an upright portion 149 of the auxiliary frame 138, as indicated at 150, is a hand-lever 151 on the inner end of which is pivotally mounted a gravity pawl 115 152 (see Figs. 1, 3 and 14), which is adapted to engage the teeth of a ratchet bar 153 secured on the under side of the table 136. By manipulating the hand-lever 151 the operator can readily slide the table 136 on its 120 ways to bring the appropriate compartment in line with the mold from which the heel has been discharged. After all of the compartments on the board have been filled the same can be removed and carried to the heel-press and a new board be inserted on the table 136.

125 After the lift is cut and before it is deposited in the mold, it is necessary to apply paste to it. This operation is accomplished 130

automatically in the following manner: Mounted on the column 2 and projecting a suitable distance outward from the same is a paste-pot 154 pivotally mounted in which, 5 at 155, is a bell-crank lever 156 carrying at one end a paste-applier 157, which may be in the form of a brush, dauber, or other similar contrivance, and at its other end carries a friction roller 158, which is adapted to 10 engage a stationary cam 159 projecting from the under side of the head 3 immediately behind each die 10 (see Figs. 12 and 13). As the head 3 revolves, after the die 10 has been depressed to cut a lift, the die carrying 15 the lift is brought over the paste-pot at the same time that the cam surface 159 engages the roller 158, the latter operation causing the paste-applier to be brought in contact with the under side of the lift and apply 20 paste thereto. As soon as the head has carried the cam 159 from over the roller the outer end of the bell-crank lever will fall, submerging the paste applier in the paste in the receptacle 154.

25 In lieu of the spring 66 for elevating the plunger of each mold I may employ the construction shown in Figs. 15 and 16, in which a bracket-arm 160, secured on the frame member 132, has an upwardly projecting 30 portion provided with a cam surface 161. The plunger 162 in this construction extends only a short distance below the mold, being supported and guided in a bearing 163 provided on the under side of the mold-carrying 35 table 62 beneath the mold, and is provided on its lower end with a friction-roller 164 which is adapted to ride over the cam surface 161 in the rotation of the table 62. By this construction the plunger is positively 40 raised, the roller reaching the highest point of the cam 161 as the mold reaches a point directly opposite the board 135. A friction screw 165, mounted in the bearing 163, engages the plunger 162 to prevent it 45 from falling after its roller passes off of the cam and to insure that it shall descend step by step under pressure exerted thereon by the plunger of the die as the lifts are successively deposited on the plunger-head 50 and upon each other.

Each of the plungers 13, not containing a nail-driver, is provided with an aperture 166 to accommodate the plunger 8, and the plunger 8 is provided at a suitable distance 55 from its lower end with a collar 167 for depressing the plunger of the die.

In the use of the ordinary heel building machine the operator is given a specification of the heel to be built, which specification 60 designates the size and thickness of each lift to be used in building the heel, so that a given number of heels of uniform height and configuration may be built; and the operator selects the various lifts from

receptacles containing the same placed 65 within his reach. In the use of the present machine the operator will be supplied with the same specification, but instead of selecting lifts, he selects the leather from which the lifts are to be cut. Thus, if No. 1 lift 70 is specified as $\frac{3}{16}$ of an inch in thickness, he would select a piece of leather of approximately this thickness and place it under No. 1 die and operate the machine to cut the lift therefrom. If No. 2 lift is specified as being 75 $\frac{1}{8}$ of an inch in thickness he would select a piece of leather of this thickness and cut a lift therefrom by actuating No. 2 die. In selecting the leather from which to cut the lifts the operator is guided entirely by his 80 eyes. The pointer 14, however, will indicate on the gage the thickness of the lift that has been cut. If a $\frac{3}{16}$ lift is required and the gage shows that the lift cut is only $\frac{1}{8}$ of an inch in thickness, the operator would 85 select a piece of leather $\frac{1}{16}$ inch in thickness and cut it with the same die containing the $\frac{1}{8}$ inch lift, thereby completing the thickness required for this particular layer. If, say, a $\frac{1}{8}$ inch lift is required and the leather 90 selected should be $\frac{3}{16}$ of an inch in thickness, the next lift would be cut from leather $\frac{1}{16}$ of an inch less in thickness than called for by the specification. Men engaged in selecting leather soon become very expert, and 95 the cutting of a lift of less or greater thickness than that called for by the specification would, in nearly all cases, be the result of inadvertence or carelessness. By the exercise of reasonable care a skilled operator can 100 invariably select a piece of leather of the thickness desired from which to cut the lift.

Having thus outlined the manner in which the lifts are selected and cut, I will now proceed to explain consecutively the operations of the machine in building a heel. The leather selected is placed on the cutting block 125 and the operator presses down on the lever 50, thereby transferring the driving belt to the fast pulley and operating 105 the shaft 44. This causes the outer end of rod 41 to rise and the hammer 40 to descend on the die 10, thereby forcing said die downward and cutting the lift. After the lift is cut the plunger 13 will be proportionately 110 raised, the pointer 14 indicating the thickness of the lift cut, and the operator proceeding in the manner above set forth should the lift be of less thickness than that called for by the specification. The lift being of 115 the proper thickness the operator next presses outward the lever 85 so that by the engagement of the pin 119 with the hook 89 of the lever 85 the arm 88 will be caused to partly rotate the shaft 76, thereby through 120 the medium of the ratchet 79, causing the head 3 to be given a partial revolution on the column 2. This will bring the die con-

taining the lift cut over one of the molds of the mold-carrying table 62, but in passing to this position the die will have passed over the paste-pot 154 and the lift cut will have 5 paste applied thereto in the manner previously described. Die No. 2 being over the cutting block, a second lift is cut in the same manner. In this operation the plunger 8 passes into the aperture 166 of the plunger 13 and the collar 167 will engage said plunger to depress it and cause it to deposit the cut lift on the plunger-head 70, thereby causing the plunger 65 to be depressed in the mold a short distance against the resistance of the spring 66. These operations are 10 repeated until the last lift of the heel is placed in the mold, when the die shown in Fig. 6 containing the nail-driver will be over the mold. The operator then drops a nail in the aperture 29, and when the next lift is cut by No. 1 die the plunger 8 will be depressed to engage the nail-driver 27 and thereby force the nail through the compiled lifts in the mold. When this has been 15 done the operator then presses the lever 91 outward so that the crank-pin 108 will engage the hook 98 of said lever so that the arm 93 will be caused to partly rotate the shaft 94 and thereby, through the medium 20 of the ratchet 115, impart a quarter of a revolution to the mold-carrying table 62. During this movement of the mold-carrying table the arm 72 will engage the lug 134 to release the pawl from engagement with 25 the teeth of the plunger 65, thereby allowing said plunger to rise and discharge the heel from the mold. During this movement also one of the striker-arms 143 will have pressed 30 back the spring-pressed bar 139 carrying the push-plate 146, and as the mold arrives opposite the board 135 the striker-arm passes into the groove 142 of the arm 141, 35 allowing the spring 140 to expand to move the push-plate toward the board, and there- 40 by transfer the heel from the mold-carrying table to the board 135. As soon as one compartment of the board 135 is filled with 45 heels it is moved by manipulating the lever 151 to bring an empty compartment into 50 position to receive the heels discharged from the mold-carrying table.

The machine illustrated herein embodies the best construction and arrangement of parts now known to me for accomplishing the objects of my invention. I wish it understood, however, that except as may be indicated in the claims, I do not desire to be limited to the precise details of construction and arrangement of parts shown in the drawings, as the same may be varied materially from the illustration without departing from the invention.

I claim:

1. A machine of the type described, com-

prising a mold, a lift-cutter movable in a horizontal plane to a position over the mold, and means for discharging the cut lifts from the cutter into said mold.

2. A machine of the type described, comprising a mold, a lift-cutter movable in a horizontal plane to a position over the mold, means for discharging the cut lifts from the cutter into said mold, and means for discharging a heel-blank from the mold.

3. A machine of the type described, comprising a mold, a lift-cutter movable in a horizontal plane to a position over the mold, means for discharging the cut lifts from the cutter into said mold, nailing mechanism co-operating with the mold, and means for discharging the heel-blank from the mold.

4. A machine of the type described, comprising a mold, a lift-cutter movable in a horizontal plane to a position over the mold, means for discharging the cut lifts from the cutter into said mold, and a nail-driver mounted in the cutter.

5. A machine of the type described, comprising a mold, a lift-cutter movable in a horizontal plane to a position over the mold, means for discharging the cut lifts from the cutter into said mold, a nail-driver mounted in the cutter, and means for actuating said nail-driver.

6. A machine of the type described, comprising a mold, a lift-cutter movable in a horizontal plane to a position over the mold, means for discharging the cut lifts from the cutter into said mold, nailing mechanism involving a nail-driver mounted in said cutter, and means for actuating said nail-driver.

7. A machine of the type described, comprising a movable member adapted to travel in a horizontal plane and having a lift-cutter mounted therein, a mold for receiving the cut lifts, said lift-cutter being movable by said member to a position over said mold, and means for discharging the lift from the cutter into said mold.

8. A machine of the type described, comprising a movable member adapted to travel in a horizontal plane and having a depressible lift-cutter mounted therein, a mold for receiving the cut lifts, said lift-cutter being movable by said member to a position over said mold, and means for discharging the lifts from the cutter into said mold.

9. A machine of the type described, comprising a movable member adapted to travel in a horizontal plane and having a depressible lift-cutter mounted therein, means for depressing the lift-cutter, a mold for receiving the cut lifts, said lift-cutter being movable by said member to a position over said mold, and means for discharging the lift from the cutter into said mold.

10. A machine of the type described, comprising a movable member adapted to travel

- in a horizontal plane and having a depressible lift-cutter mounted therein, means for depressing said lift-cutter, a plunger mounted in the lift-cutter for discharging the lifts therefrom, a mold for receiving the 5 cut lifts, said lift cutter being movable by said member to a position over said mold, and means for depressing said plunger.
11. A machine of the type described, comprising a mold, a horizontally-rotatable head, a lift-cutter mounted in said head and movable thereby to a position over the mold, and means for discharging the cut lifts from the cutter into said mold.
12. A machine of the type described, comprising a mold, a horizontally-rotatable head, a series of lift-cutters mounted in the head and movable thereby in succession to a position over the mold, and means for discharging the cut lifts from the cutters into 10 said mold.
13. A machine of the type described, comprising a rotatable table carrying a series of molds, a rotatable head, a series of lift-cutters mounted therein and movable thereby successively to a position over each of said 15 molds in succession, and means for discharging the cut lifts from a plurality of said cutters into each mold in succession.
14. A machine of the type described, comprising a rotatable table carrying a series of molds, a rotatable head, a series of lift-cutters mounted therein and movable thereby successively to a position over each of 20 said molds in succession, means for discharging the cut lifts from said cutters, and means for rotating said table at will to bring its molds successively to a position to receive the cut lifts discharged from said 25 cutters.
15. A machine of the type described, comprising a rotatable table carrying a series of molds, a rotatable head, a series of lift-cutters mounted therein and movable thereby successively to a position over each of 30 said molds in succession, means for discharging the cut lifts from said cutters, means for rotating said table at will to bring its molds successively to a position to receive the cut lifts discharged from said 35 cutters, a nailing device coöperating with said molds, and means for actuating the same.
16. A machine of the type described, comprising a movable member having a lift-cutter 40 mounted therein, a mold for receiving the cut lifts, said lift-cutter being movable by said member to a position over said mold, an automatic paste-applier located in the zone of movement of the lift-cutter, and means for discharging the lift from the cutter into said mold.
17. A machine of the type described, comprising a movable member having a lift-cutter mounted therein, a mold for receiving the 45 cut lifts, said lift-cutter being movable by said member to a position over said mold, and means for depressing said member to a position over said mold, a paste-applier located in the zone of movement of said lift-cutter, means carried by said member for actuating said paste-applier as the cutter passes over the same, and means for discharging the cut and pasted lift from the cutter into said mold.
18. A machine of the type described, comprising a movable member having a lift-cutter mounted therein, a mold for receiving the 50 cut lifts, said lift-cutter being movable by said member to a position over said mold, a paste-pot located in the zone of movement of said lift-cutter, a paste-applier pivotally mounted in said paste-pot, a cam carried by 55 said member for actuating said paste-applier as the cutter passes over the same, and means for discharging the cut and pasted lift from the cutter into said mold.
19. A machine of the type described, comprising a movable member adapted to travel in a horizontal plane and having a series of lift-cutters mounted therein, a mold for receiving the cut lifts from the various lift-cutters, said lift-cutters being movable in 60 succession by said member to a position over said mold, and means for discharging the lifts from the cutters into said mold.
20. A machine of the type described, comprising a movable member adapted to travel in a horizontal plane and having a series of 65 depressible lift-cutters mounted therein, a mold for receiving the cut lifts from the various cutters, said cutters being movable in succession to a position over said mold, means for discharging the lift from each cutter into said mold, a nailing device mounted in the last cutter of a series, and means for actuating the same.
21. A machine of the type described, comprising a rotatable head having a series of 70 depressible lift-cutters mounted therein, a mold for receiving the cut lifts from the various cutters, a plunger mounted in each lift-cutter, a nail-driver also mounted in one 75 of said lift-cutters, a hammer for actuating said lift-cutters, a plunger for actuating said nail-driver, driving mechanism for the machine, means for operatively connecting said hammer and plunger with the driving mechanism at will, and means for rotating the said head from the driving mechanism 80 at will.
22. A machine of the type described, comprising an automatically movable member having a lift-cutter mounted therein, a mold for receiving the cut lifts, said lift-cutter being movable in a horizontal plane by 85 said member to a position over said mold, and automatic means for discharging the lift from the cutter into said mold.
23. A machine of the type described, comprising an automatically movable member having a lift-cutter mounted therein, a mold for receiving the cut lifts, said lift-cutter 90

being movable in a horizontal plane by said member to a position over said mold, automatic means for discharging the lift from the cutter into said mold, and automatic means for discharging the heel-blank from said mold.

24. A machine of the type described, comprising an automatically movable member having a lift-cutter mounted therein, a mold for receiving the cut lifts, said lift-cutter being movable by said member to a position over said mold, automatic means for applying paste to the cut lift, automatic means for discharging the lift from the cutter into said mold, automatic means for nailing said lifts, and automatic means for discharging the heel-blank from the mold.

25. A machine of the type described, comprising an automatically movable member having a lift-cutter mounted therein, a mold for receiving the cut lifts, said lift-cutter being movable by said member to a position over said mold, automatic means for applying paste to the cut lift, automatic means for discharging the lift from the cutter into said mold, automatic means for nailing the compiled lifts, automatic means for discharging the heel-blank from the mold, and automatic means for removing the completed heel-blank.

26. In a machine of the type described, a movable member having a lift-cutting device mounted therein, a mold for receiving the cut lifts, said lift-cutter being movable in a horizontal plane by said member to a position over said mold, a lift-discharging device, a heel-blank-discharging device, driving mechanism, means operatively associated with the driving mechanism for actuating the lift-cutting and the lift-discharging devices, means acting automatically to discharge the heel-blank from the mold in the operation of the machine, and mechanism adapted to be connected with the driving mechanism at will for actuating said movable member.

27. In a machine of the type described, a movable member having a lift-cutting device mounted therein, a mold for receiving the cut lifts, said lift-cutter being movable by said member to a position over said mold, a lift-discharging device, a heel-blank-discharging device, a heel-blank-removing device, driving mechanism, means operatively associated with the driving mechanism for actuating the lift-cutting, the lift-discharging, and the heel-blank-removing devices, means acting automatically to discharge the heel-blank from the mold in the operation of the machine, and mechanism adapted to be connected with the driving mechanism at will for actuating said movable member.

28. In a machine of the type described, a rotatable head having a series of lift-cutting devices mounted therein, a rotatable table

having a series of molds mounted therein for receiving the cut lifts, a lift-discharging device mounted in each lift-cutting device, a heel-blank-discharging device associated with each mold, driving mechanism, means operatively associated with the driving mechanism for actuating the lift-cutting and the lift-discharging devices, means acting automatically to discharge the heel-blank from the molds in the operation of the machine, and mechanisms adapted to be connected with the driving mechanism at will, respectively, for actuating the rotatable head and the rotatable table.

29. In a machine of the type described, a rotatable head having a series of lift-cutting devices mounted therein, a rotatable table having a series of molds mounted therein for receiving the cut lifts, said lift-cutting devices being movable in succession by said head to a position over one of said molds, a lift-discharging device mounted in each lift-cutting device, a heel-blank-discharging device associated with each mold, a heel-blank-removing device, driving mechanism, means operatively associated with the driving mechanism for actuating the lift-cutting, the lift-discharging and the heel-blank-removing devices, means acting automatically to discharge the heel-blank from a mold in the operation of the machine, and mechanisms adapted to be connected with the driving mechanism at will, respectively, for actuating the rotatable head and the rotatable table.

30. In a machine of the type described, in combination with a movable member having a lift-cutting device mounted therein, a movable member having a mold mounted therein, said lift-cutting device being movable by said member to a position over said mold, an automatic heel-blank-discharging device associated with the mold, driving mechanism, mechanisms adapted to be connected with the driving mechanism at will, respectively, for moving said movable members, and means carried by a fixed part of the machine for releasing the heel-blank-discharging device in the movement of the mold-carrying member.

31. In a machine of the type described, in combination with a movable member having a lift-cutting device mounted therein, a movable member having a mold mounted therein, said lift-cutting device being movable by said member to a position over said mold, a spring-controlled depressible plunger working in the mold and having a ratchet, a pivotally-mounted member having a pawl engaging said ratchet and normally preventing the rise of the plunger, a stop on the machine adapted to be engaged by said member to turn the pawl out of engagement with said ratchet and allow the plunger to

rise for discharging the heel-blank, and mechanisms adapted to be connected with the driving mechanism at will, respectively, for moving said movable members.

5 32. In a machine of the type described, in combination with a lift-cutting and delivering mechanism, a mold for receiving the cut lifts, means for discharging a heel-blank from the mold, a slidable table mounted adjacent to said mold, ratchet mechanism for moving said table, and a board mounted thereon provided with a series of parallel compartments for receiving heel-blanks.

10 33. In a machine of the type described, in combination with lift-cutting and delivering mechanism, a rotatable table carrying molds for receiving the cut lifts, mechanism for discharging heel-blanks from said molds, and heel-removing mechanism comprising 15 a spring-pressed bar carrying a heel-remover, an arm carried by said bar, and a striker carried by said table adapted to engage said arm during a portion of the movement of said table, and then to pass out of 20 engagement therewith, whereby to release the bar and permit its spring to throw the heel-remover outward.

25 34. In a machine of the type described, heel-removing mechanism comprising a rotatable table carrying molds and having 30 strikers depending at intervals from its under side, a spring-pressed bar having a curved arm projecting into the path of said strikers and provided with a transverse 35 groove near its base, whereby, in the move-

ment of said table, one or the other of said strikers will engage said arm and carry the bar inward against the resistance of its spring, and will then enter the groove and release said arm to permit the bar to be 40 thrown outward by its spring, and a heel-remover mounted on said bar and adapted to be moved across the molds in the operation of said spring-pressed bar.

35. In a machine of the type described, 45 heel-removing mechanism comprising a spring-actuated heel-remover, a movable member carrying molds and having means for discharging heel-blanks from the molds, and means carried by said member for alternately compressing and releasing the 50 spring of the heel-removing mechanism.

36. A machine of the type described, comprising a movable member having a 55 compressible lift-cutter mounted therein, means for actuating said cutter, a rotatable cutting block mounted beneath said lift-cutter, means for rotating said block, a mold for receiving the cut lifts, the said lift-cutter being movable by said member to a position 60 over said mold, and means for discharging the lifts from the cutter into said mold.

In testimony whereof, I have hereunto set my hand in presence of two subscribing witnesses.

WILLIAM WOLFE.
